G. B. PENNEBAKER

CHANGEABLE EXHIBITOR

Original Filed April 11, 1925

FIG. 1

FIG. 2

Patented Mar. 1, 1927.

1,619,088

UNITED STATES PATENT OFFICE.

GEORGE B. PENNEBAKER, OF OAKLAND, CALIFORNIA, ASSIGNOR TO FRED STARR AND WILLIAM P. GREEN, BOTH OF OAKLAND, CALIFORNIA.

CHANGEABLE EXHIBITOR.

Application filed April 11, 1925, Serial No. 22,476. Renewed December 6, 1926.

My invention relates in general to changeable exhibitors, and has particular reference to a device of this character for progressively exhibiting display advertising.

5 The salient features of my invention are concerned with the combination of a counter inkstand, preferably of the well-known "Sengbusch" self-closing type, and advertising exhibitor. The device is constructed 10 to be placed upon a writing counter such as employed in banks, for example, and is adapted to automatically change the advertising display upon the use of the inkstand.

15 Devices of this character which I am familiar with, invariably do not register the advertisement with the sight opening provided therefor and hence are not efficient. My improvement seeks to remedy this deficiency, and I accomplish the same by providing a definite starting point and a definite limiting and stopping point.

20 Other objects and advantages and the features of construction of the invention, will appear in the subjoined description of the 25 accompanying sheet of drawings, in which:

Figure 1 is a perspective view of the combination device; Fig. 2 is a plan, on an enlarged scale, with the cover removed; Fig. 3 is a central vertical section through the 30 inkstand and casing, and full end view of the drum; Fig. 4 is a rear view, greatly enlarged, on the line 4-4 of Fig. 3 to more clearly show certain parts and some of the parts are in section; and Fig. 5 is a view 35 similar to that of Fig. 3 and showing the manner of operating the device.

40 Referring to the drawings in detail: I propose to construct the device in the form of a metallic cabinet 1 of a size and design suitable for the purpose, and the same includes a base 2 and a removable cover 3. The cover may be made with an inclined top 4 having a recess 5 and inkstand opening therein, and a glass-covered window 6 above 45 the same. The recess has a flat portion 7 surrounding the flared top 8 of the inkstand, and the window 6 includes a marginal frame 9 for the glass.

50 The fundamental principle of the device is to change the advertising displayed through the window 6 every time a writing pen is inserted into the inkwell. To accomplish this end in a positive and practical

manner, I employ a drum 10 fixedly mounted upon a shaft 11 and housed within the 55 cover 3, and which drum carries a series of advertising exhibits such as shown in Fig. 2 for example, properly spaced so that each exhibit in turn will show through the window 6 while the others of the series are covered. The drum shaft is preferably pointed at its respective ends and is supported in corresponding bearings 12 and 13 mounted upon inner upright walls 12' and 13'. The 60 said walls are bent up from the inner base 10'. The cover 3 may be attached to the whole assembly as by knurled screws 3' screwed into tapped holes 4' in the said upper 65 inner walls.

70 The inkstand best suited for my improvement is what is known on the market as the "Sengbusch" a self-closing type, shown in the drawings in light lines. The inkstand comprises a glass receptacle 14, with a restricted throat or neck 15 surrounded by a 75 partition super-well 16 which communicates with the main well 17 by a duct 18. A float 19 in the main well is provided with a reduced part 20 extending into the neck 15 and has a termination contacting the underside of the top 8 which latter caps the inkstand. The shouldered bottom 21 of the neck provides an abutment for the annular flange on the large end of the float. Vertical ducts 22 in the inner surface of the 80 throat or neck provide channels through which the ink feeds to the top of the float 85 when the float is pressed downwardly by the penpoint 23.

90 The glass receptacle 14 of the inkstand is bedded in a wooden holder 24 fitted in a compartment formed by the walls 12', 13', base 10' and cross-wall 25. A cover is made for the inkstand which includes the flared top 8. The construction of the inkstand is 95 conventional and needs no further detailed description.

100 Anchored in the reduced end of the float is a wire 26, the free end 27 of which is hooked over the projecting end of a lever 28 fixed to a shaft 30 suitably supported in bearings 31 and 32 in the upright walls 12' and 13'. This shaft also carries a counterbalance 33 which is in the form of a right-angled metal bar mounted in fixed relation 105 to the shaft 30 so as to assure a sensitive

balance of the operating parts. In other words, the counterbalance serves to assist the introduction of the pen into the well to press the float down and aid the float and 5 said parts to return to normal position when the pen has been retracted.

Fixedly secured to the shaft of the drum 10 is a ratchet wheel 34 having as many teeth as the desired number of advertising 10 zones to be on the drum. In this case I have chosen six teeth, and each of the latter are adapted to be engaged by a swinging hook 35 pivotally connected as at 36 to a lever 37 fixed to shaft 30. The function of 15 this hook is to reach under one of the teeth and engage it when the lever is in normal or at rest position (as best shown in Fig. 3) so that when the pen is inserted into the inkwell and the lever 28 pulled down, the 20 opposite lever 37 in raising will impart an upward pull to the hook and turn the ratchet wheel and through it the drum, to change the advertising displayed through the window 6.

25 To properly time the rotation of the drum so as to insure the exact spacing of the advertising with respect to the area of the window and thus prevent a part of two advertisements being shown through the 30 window at one time, I provide suitable stops for checking or arresting the rotation of the drum. These stops preferably comprise a series of projecting pins 38 arranged in spaced relation on one side of the drum so 35 that when the lever 28 is pulled down and its opposed lever 37 elevated to turn the drum, a finger 39 fixed on the end of the lever 37 will be raised to act as an abutment for one of the pins 38, thus momenta- 40 rily arresting the rotation of the drum. When the float has been released the counterweight restores the balance of the lever assembly to normal position again. In ap- 45 proaching the normal position the end of the lever 37 carrying the finger 39 will be lowered which will release the abutment of the pin. To again arrest the drum and limit the movement of the same, I provide a loosely pivoted gravity weight 40 adja- 50 cent the finger 39, which weight will always hang plumb and engage the tooth opposite the hook 35 (as best shown in Fig. 3) and lock the wheel in place, so to speak, from continued rotation if one should thrust the 55 pen smartly and quickly into the inkwell.

From the foregoing description taken in connection with the accompanying drawings, the advantages of the construction and method of operation will be readily under- 60 stood by those skilled in the art to which the invention appertains, and while I have described the principle of operation, together with the device which I now consider to be the best embodiment thereof, I desire 65 to have it understood that the device shown

is merely illustrative and that such changes may be made, when desired, as fall within the scope of the appended claims.

Having thus described my invention, what I claim as new and desire to secure by Letters Patent of the United States is the following:

1. In combination with an inkstand of the "Sengbusch" type having a reciprocating pen-actuated float, a rotating drum having advertising matter around the circumference of the same, a housing for the drum, a window in the housing for displaying progressive portions of said advertising matter, means connected to the float in the ink adapted to rotate the drum upon reciprocation of the float in one direction, and gravity-actuated means for arresting movement of the drum to align the advertising matter in display relation with said window. 85

2. A changeable exhibitor comprising an inkstand having a reciprocating float, a rotary drum with advertising matter arranged in series on the circumference thereof, a housing for the drum, a window in the housing through which said advertising matter on the drum is visible, motion converting means connecting the float with the drum for converting the reciprocating movement of the former into rotary movement for the latter, means for momentarily arresting the rotary movement of the drum, and gravity-actuated means for limiting and stopping the movement of the drum. 95

3. A changeable exhibitor comprising an inkstand having a reciprocating float, a rotary drum with advertising matter arranged in series on the circumference thereof, a housing for the drum, a window in the housing through which said advertising matter on the drum is visible, motion converting means connecting the float with the drum for converting the reciprocating movement of the former into rotary movement for the latter, means for momentarily arresting the rotary movement of the drum, and gravity-actuated means for limiting and stopping the movement of the drum, said motion converting means comprising a fulcrumed lever assembly connected to the float, a ratchet wheel on the drum and means carried by said lever assembly for engaging said wheel to rotate the same and through it the drum. 115

4. In a changeable exhibitor of the class described, a rotary drum, a ratchet wheel on the side thereof, a lever adjacent said ratchet wheel, a pivoted hook on said lever adapted to engage said ratchet wheel, a shaft to which said lever is fixed, a second lever fixed to said shaft, means for rocking said levers to rotate the drum through the medium of said ratchet wheel and pivoted hook, and means for arresting the rotation of said drum comprising a series of projecting pins 130

on the side of said drum, a stop on the first- 5. The combination set forth in claim 4 named lever presented in the path of said including a housing in which the drum is 10 pins when the latter lever is rocked in one mounted, a window in the housing, and a direction and a gravity weight on the lever series of advertising matter on the circum- 5 to rock the same in the opposite direction, fference of the drum adapted to be displayed and said weight adapted to engage the through said window. ratchet wheel to cause a predetermined limit In testimony whereof, I affix my signature. of movement of the said drum.

GEORGE B. PENNEBAKER.
